UNITED STATES PATENT OFFICE.

DORA M. SMITH, OF LOS ANGELES, CALIFORNIA.

DESIGN FOR A JEWEL-CASE.

SPECIFICATION forming part of Design No. 29,319, dated September 6, 1898.

Application filed August 17, 1897. Serial No. 648,601. Term of patent 3½ years.

To all whom it may concern:

Be it known that I, DORA M. SMITH, a citizen of the United States, residing at Los Angeles, in the county of Los Angeles and State of California, have invented a new and original Design for Jewel-Cases; and I do declare the following to be a full, clear, and exact description of the invention, such as will enable others skilled in the art to which it appertains to make and use the same, reference being had to the accompanying drawing, and to the letters of reference marked thereon, which forms a part of this specification.

The design has for its characteristics the following features: a hollow body rounded in general outline, with flattened top and bottom and a circular opening in the top and a pair of projections extending flaringly from different points in the sides of the body and having the configuration of human legs, the upper portions of which are clothed in suitable coverings.

In the drawing which accompanies and forms part of this specification and illustrates the design in perspective, the letter *a* designates the hollow body rounded in general outline and whose surface has a wicker-work ap-

pearance. Said body has a circular opening *a'* in its flattened top. The projections in the form of human legs are designated by the letter *b* and the clothing covering the upper portions of the legs by the letter *b'*. It will be noticed that the legs project from different points of the body and spread with the toes turned out and upward, after the natural appearance of a person seated on a floor or the ground with legs stuck out in front. The coverings *b'* have the "full" appearance of bloomers.

The whole makes a very unique and effective design for a receptacle for jewelry or other small articles.

Having thus described my invention, what I claim as new, and desire to secure by Letters Patent, is—

The design for a jewel-case substantially as shown and described.

In testimony whereof I affix my signature in presence of two witnesses.

DORA M. SMITH.
